CONTAINER FOR TABLE-TENNIS BAT

Stig Gunnar Hjelmquist, Box 6,
S-573 01, Tranås, Sweden

Filed Nov. 6, 1973, Ser. No. 413,263

Claims priority, application Sweden May 7, 1973

Term of patent 14 years

Int. Cl. D9—99

U.S. Cl. D9—192

FIG. 1

FIG. 2

FIG. 3

FIG. 4

FIG. 5

FIG. 1 is a perspective view of a container for a table-tennis bat showing my new design;

FIG. 2 is a top plan view thereof;

FIG. 3 is a right edge elevational view;

FIG. 4 is a bottom plan view; and

FIG. 5 is a front edge elevational view.

I claim:

The ornamental design for a container for table-tennis bat, substantially as shown and described.
